UNITED STATES PATENT OFFICE.

RODOLPH STUART O'NEIL, OF LONDON, ENGLAND.

SIGNALING THE POSITION OF A SHIP'S HELM.

1,377,427.

Specification of Letters Patent. Patented May 10, 1921.

Application filed February 11, 1920. Serial No. 357,890.

To all whom it may concern:

Be it known that I, RODOLPH STUART O'NEIL, a subject of the King of Great Britain, and a resident of London, England, have invented certain new and useful Improvements in and Connected with Signaling the Position of a Ship's Helm, of which the following is a specification.

This invention relates to improvements in and connected with signaling the position of a ship's helm, and has reference to apparatus for enabling a captain or helmsman at all times to inform himself as to the position of the ship's rudder at any moment, of that character where a switch associated with the rudder movement coöperates with stationary contacts to make circuits to signaling lamps or indicators located in the wheel house or other desired position on the ship.

In such apparatus it is important that there shall be no possibility of error in conveying to the signal indicator the position of the rudder and for this reason it is necessary to connect the contact switch with the rudder post or steering member so that any want of alinement or backlash effect will not be communicated to the switch in such a manner as to interfere with the contact effect required to operate the signaling device correctly. For this purpose according to my invention a flexible joint is interposed as the connecting link between the rudder post and the switch as hereinafter described.

It has been suggested to provide a switch arm connected directly to and moving with the rudder post but a difficulty which has been experienced in practice arises from the fact that the rudder moves longitudinally of its axis to some extent and it is difficult to insure correct contact between the moving switch arm and its coöperating stationary contacts. The important feature of my present invention is the connection of the moving member of the switch to the rudder post through a connection adapted to transmit the torque of the rudder directly but to accommodate itself to the axial movements of the rudder post.

In the accompanying drawings I have illustrated my invention, Figure 1 being a diagrammatic elevation of the connection of the rudder to the contact drum or brush and also the electrical connections to the indicator.

Fig. 2 is a detail of the rudder part and connections.

Fig. 3 is a section on line 3—3, Fig. 2.

Referring to the drawing, the numeral 1 designates the rudder post which is connected by a rod 2 and universal couplings 3 and 4 to a contact drum 5. The member 3^a of the universal coupling 3 is slidably mounted in a bearing 3^b in or upon the rudder post, a key or feather 3^c being provided to insure rotation of said member 3^a with the rudder and also arranging said member for sliding movement, and a spring 3^d is provided to give a spring mounting to the member 3^a. The said key is here shown as 70 movable in a slot 3^e in one side of the member 3^b. This arrangement of mounting is important in practice in order to compensate for relative axial movements between the rudder post and the contact drum. The 75 contact drum 5 has its contacts arranged to correspond with certain positions of the rudder. For the present it is only necessary to consider three positions, corresponding to the central position of the rudder and 80 positions both to "port" and "starboard." The contact drum 5 moves with the rudder post 1, and I provide a pair of contacts 7 and 8, one corresponding to "port" and the other to "starboard." These contacts 7 and 8 are 85 arranged on the drum on either side of the central position and one or other of them serves, by coöperation with a stationary contact either 7^b or 8^b, to complete the circuit of an electric lamp or indicator 7^a or 8^a 90 respectively each of a particular color. With the rudder in precisely the central position neither of the drum contacts 7 and 8 will engage their respective coöperating stationary contacts 7^b and 8^b and no fresh indication will be given, but any deviation of the rudder from the central position will cause contact to be made between one or other of the drum contacts 7 and 8 and in one or other of the coöperating contacts 7^b or 8^b and one 95 or other of the lamps 7^a or 8^a will be illuminated or one or other of two indications made. The lamp or indicator signal associated with the "port" contact 7 may be one color and that associated with the "starboard" contact 8 another so that immediately either of the lamps becomes illuminated the helmsman or other person provided with indication lamps will know that 100 the rudder has moved from the central position.

tion and the color of the light or indicator exhibited will inform him as to the direction of the movement.

This principle can of course be indefinitely extended and further contacts and lamps or indicators may be provided to indicate further positions of the rudder. For example the central position may be indicated by a white light or no light at all, five degrees to 10 "starboard" by a green light, five degrees to "port" by a red light, fifteen degrees "starboard" by a combined green and white, fifteen degrees to "port" by a combined red and white, while hard over on the port side 15 may be indicated by two red lights and hard over on the "starboard" side by two green lights. These various positions are indicated by reason of drum contacts 9 connected together in pairs coöperating with stationary contacts 10, through which circuits to 20 indicator coils (or lamps) 11 are established. Thus the various actual positions mentioned of the rudder will be signaled.

It has been noted that the central position 25 of the rudder may be indicated by a white light or indicator and in the diagram this lamp or indicator is designated 6. Current passes to the drum from the positive line to the stationary contact 6^a with which the 30 drum contact 6^b coöperates. In the central position of the rudder a stationary contact 6^c coincides with a drum contact and when the rudder moves, say five degrees, in either 35 direction the drum contact becomes separated from the stationary contact and the white light goes out, a colored light being substituted.

What I claim and desire to secure by Letters Patent is:—

40 1. A connection for use between the rotatable contact maker of electric signaling apparatus and a ship's rudder post, comprising

ing a rod, universal couplings at the ends of the rod, one for attachment to such contact maker, a slidable member attached to the 45 other coupling, a bearing for attachment to the rudder post and in which said slidable member is mounted for sliding movement and for turning movement therewith, to permit axial movement between the contact 50 maker and the rudder post.

2. A connection for use between the rotatable contact maker of electric signaling apparatus and a ship's rudder post, comprising 55 a rod, universal couplings at the ends of the rod, one for attachment to such contact maker, a slidable member attached to the other coupling, a bearing for attachment to the rudder post and in which said slidable member is mounted for sliding movement 60 and for turning movement therewith, to permit axial movement between the contact maker and the rudder post, and a spring between the opposing faces of the slidable member and bearing.

65 3. A connection for use between the rotatable contact maker of electric signaling apparatus and a ship's rudder post, comprising a rod, universal couplings at the ends of the rod, one for attachment to such contact maker, a slidable member attached to the other coupling, a bearing for attachment to the rudder post and in which said slidable member is mounted for sliding movement and for turning movement therewith, to 70 permit axial movement between the contact maker and the rudder post, said bearing having longitudinal grooves in the interior of its side faces and said bearing having keys engaging said grooves, and a spring 75 between said bearing and slidable member.

In witness whereof I affix my signature.

RODOLPH STUART O'NEIL.
